UNITED STATES PATENT OFFICE.

KENNETH J. TOBIN AND WILLIAM W. DARROW, OF CHICAGO, ILLINOIS, ASSIGNEES
TO CAMEL COMPANY, OF CHICAGO, ILLINOIS, A CORPORATION OF ILLINOIS.

SIDE-DOOR CONSTRUCTION.

Application filed August 14, 1924. Serial No. 732,04.

To all whom it may concern:

Be it known that we, KENNETH J. TOBIN and WILLIAM W. DARROW, citizens of the United States, residing, respectively, at 5 Chicago, in the county of Cook and State of Illinois, and at Chicago in the county of Cook and State of Illinois, have jointly invented certain new and useful Improvements in Side-Door Constructions, of which 10 the following is a specification.

The present invention relates to side door construction.

More particularly the present invention relates to side door constructions for rail- 15 way cars of the box car type.

Box cars for certain purposes, as for example box cars used in the transportation of automobiles and the like, must have side door openings of more than the usual width. 20 Cars of this sort are commonly provided, in addition to the usual sliding door, with a secondary or supplementary door, sometimes narrower than the main door though not necessarily so, which secondary or sup- 25plementary door is slidably movable to provide a door opening of extraordinary width but which may be stationarily held when a door opening of such extraordinary width is not required. When the door opening of 30 extraordinary width is not required, said secondary or supplementary door acts as a part of the car wall.

The present invention has for one of its objects the provision of an improved construction wherein a door opening of extraordinary width may be provided without weakening the car structure.

A further object is to provide an inexpensive and practical construction of car door which while retaining the advantage of extraordinary door opening and car rigidity has the advantages of simplicity and ready availability for carrying grain or other finely divided lading.

A further object is to provide a side door construction involving a main door, a supplemental door and a movable door jamb, which door jamb will automatically lock it- 45self in closed position but which may be readily unlocked when it is desired to move

said jamb to provide a door opening of extraordinary width.

A further object is to provide a side door construction involving a main door, a supplemental door and a movable door jamb, 55 which side door construction combines ease of operation with sturdiness.

A further object is to provide a side door construction of the double-door type where- 60 in the supplemental door is so constructed that it will lock automatically when closed, and will be securely and rigidly held against accidental opening.

A further object is to provide a side door construction of the double-door type adapt- 65ed for ready application to existing cars.

A further object is to provide a side door construction of the double-door type which construction involves a movable door jamb wherein said door jamb provides a substan- 70tially vertical bracing support for both the main and supplemental doors when said doors are in closed position.

A further object is to provide side door construction in which the number of fittings 75 is reduced to a minimum and in which the number of kinds of fittings is reduced to a minimum.

A further object is to provide side door construction so arranged that the danger 80 of the construction becoming inoperative through the accumulation of ice, snow, or other foreign matter, is reduced to a minimum.

A further object is to provide a side door 85 construction which adapts itself for the efficient application of grain doors.

A further object is to provide a side door construction involving a movable jamb, which jamb will become automatically 90 locked in place when in closed position to form a brace between the side plate and side sill of a railway car, but which may be released without difficulty.

A further object is to provide a side door 95 construction involving a main door and a supplemental door, which construction will be simple and rigid, economical to fabricate and install, which will contain a minimum of parts, and which provides efficient hold- 100

ing means for grain doors or other types of co-operation at present employed on railway box cars.

Further objects will appear as the description proceeds.

Referring to the drawings—

Figure 1 is a fragmentary view, in side elevation, of a box car showing the main and supplemental doors in closed position.

10 In this view the movable jamb or post is shown in dotted lines in its locked position.

Figure 2 is a sectional view, taken along the plane marked by the arrows 2—2 of Figure 1;

15 Figure 3 is a fragmentary view in elevation, the floor of the car being shown in section, looking at the doors in their closed positions from the inside of the car;

20 Figure 4 is a fragmentary view, on a larger scale, showing the supplementary door, the door jamb movable therewith, and the mechanism for locking said door and jamb in closed position;

25 Figure 5 is a fragmentary view of the structure illustrated in Figure 4, looking in the direction indicated by the arrow 5 of Figure 4;

30 Figure 6 is a fragmentary perspective view showing the supplementary door and door jamb movable therewith with the upper door stop removed and the main door partly open;

Figure 7 is a sectional view taken along the plane indicated by the arrows 7—7 of Figure 3;

35 Figure 8 is a perspective view of a stop plate or detent member which may be used either at the top or bottom of the car;

40 Figure 9 illustrates a modified form of movable door jamb particularly applicable to steel door construction;

Figure 10 is a sectional view taken along the plane indicated by the arrows 10—10 of Figure 9;

45 Figure 11 is a fragmentary view illustrating a modified form of fitting particularly adaptable for use with a wooden post or jamb;

50 Figure 12 is a fragmentary view in elevation looking in the direction of the arrow 12 of Figure 4;

Figure 13 is a sectional view, taken along the plane indicated by the arrows 13—13 of Figure 12;

55 Figure 14 is a fragmentary view in elevation, looking from the interior of the car, illustrating a modified structure particularly adaptable for use with grain doors;

60 Figure 15 is a sectional view taken along the plane indicated by the arrows 15—15 of Figure 14;

Figure 16 illustrates a slight modification of structure shown in Figures 14 and 15;

65 Figure 17 illustrates a modification of the structure shown in Figure 16; and

Figure 18 is a fragmentary view illustrating the construction of a detent member used in the practice of the present invention.

Referring first to Figures 1 and 2, the numeral 1 illustrates the side wall and the numerals 2 and 3 indicate respectively the side plates and side sills of a railway box car. The numeral 4 indicates a sliding door, which for purposes of description, will be referred to in this specification as the main door. Said main door is adapted to cooperate with the post or jamb 5, which jamb is indicated in dotted lines in Figure 1. Preferably, though not necessarily, secured to the jamb 5 is the door 6, also slideable longitudinally of the car, which door 6 for the purposes of convenience is referred to in this specification as the supplementary door. According to the preferred embodiment of the present invention, the supplementary door 6 will be rigidly united to the jamb 5. Said jamb 5 is movable with the supplementary door 6 from the position indicated in full lines in Figure 2 to the position indicated in dotted lines in said figure. Mechanism is provided for releasably securing the jamb 5 in the position shown in full lines in Figure 2, which mechanism will be described in detail hereinafter. The numeral 7 indicates as a whole certain push and pull mechanism, whereby the main door 4 may be readily moved relative to the supplementary door 6 either in opening or closing movement. The mechanism 7 forms no part of the present invention and need not be described herein. The numeral 8 indicates as a whole certain locking and sealing mechanism whereby the main door 4 may be locked in its closed position. The doors 4 and 6 illustrated in Figure 1 are bottom hung, suitable track means and rollers being provided for facilitating the sliding movement of said doors. It will be apparent, however, as the description proceeds that the present invention is independent of the means for hanging the doors.

Referring now to Figures 3, 4, 5 and 6, it will be noted that the supplementary door 6 has secured thereto the vertical post or jamb indicated in its entirety by the numeral 9. As best shown in Figures 4 and 6, the post may comprise two angles 10—10 having edges abutting or substantially abutting to form a channel. As shown in Figure 6, the doors 4 and 6 are provided, along adjacent vertical edges, with Z-bars 11 and 12 respectively, which cooperate to form a close joint when said doors are in closed position. The inner flange of the Z-bar 12 is arranged along the inner surface of the supplemental door 6. According to the embodiment of the present in-

vention illustrated in Figures 6 and 7, there is a small difference between the angles 10-10 making up the post or jamb 9 in order that the inwardly disposed edges of the angles 10-10 may lie in a plane substantially parallel with the car side. It will be understood, of course, that if desired a filler plate of the thickness of the inner flange of Z-bar 12 may be provided below that angle 10 which is disposed at the left as the parts are viewed in Figure 6, whereby the two angles 10-10 of the post or jamb 9 may be identical and still have their inwardly disposed edges in a plane parallel with the car side. Any preferred securing means, as for instance rivets, may be used for fastening the angles 10-10 to the supplementary door 6.

Mounted within the channel-shaped post 9 formed by the angles 10-10 are a pair of housings 13-13 located at the top and bottom of said channel-shaped post or jamb 9. Said housings may be held in position longitudinally of the post 9 by any preferred means. By reason of this construction the post 9 will act as a tie between the upper and lower portions of the car, for reasons which will be referred to hereinafter. One means for supporting the housing is illustrated in Figure 10, in which each housing 13 is provided with a plurality of studs 14-14 extending in a plane parallel with the side walls of the car. Said studs 14-14 extend through suitable holes in the laterally disposed flanges of the channel-shaped post 9, said slots being indicated by the numerals 15-15. Referring to the upper housing 13, one of the slots 15 houses trunnions 16 (only one being shown), which trunnions are held in place by the adjacent flange of the channel-shaped post 9. Said trunnions 16 form pivot members for the catch member 17. The catch member 17 is provided with a catch portion 18 adapted to engage with certain detent mechanism, to be described hereinafter. The catch member 17 is also provided with an operating arm 19. Referring to the lower housing 13, one of the slots 15 receives the lever 20, which lever is provided with a catch portion 21 adapted to engage with certain detent mechanism to be described hereinafter. Said lever 20 also has an end portion 22 which preferably projects laterally of the channel-shaped post 9 on the same side as the operating arm 19 of the catch member 17. Mounted in cooperative relationship with the catch member 17 and with the lever 20 is the trip member 23. Said trip member 23 may be an elongated bar having the handle portion 24, which may be conveniently grasped by an operator. The upper

end of said trip member 23 is provided with a turned over portion 25, which, when the trip member 23 is raised, will cause the operating arm 19 of the catch member 17 to swing upwardly and outwardly whereby to lower the catch portion 18 of said catch member 17. It may be stated at this point that the catch member 17 is so designed that it will normally assume a position with the operating arm 19 in its lowermost position to hold the catch portion 18 in its uppermost or engaging position. The lower portion of the trip member 23 is provided with an aperture 26 loosely encircling the end portion 22 of the lever 21. Straps 27 (Figure 4) may be provided for holding the trip member 23 in place. Furthermore, a tongue 28 may be struck out from the adjacent flange of one of the angles 10, which tongue may ride in slots 29 of the trip member 23 to guide said trip member in a vertical movement. It will be obvious that when the trip member 23 is raised against the influence of gravity, the catch member 17 will be moved to lower the catch portion 18 thereof and the lever 20 will be moved to raise the catch portion 21 thereof.

Figure 8 illustrates in perspective a detent member 29, one of which may be secured to the side plate at the top of the car and another of which may be secured to the side sill at the bottom of the car. Said detent members 29 may be of malleable iron or cast steel and are provided with suitable apertures 30-30 through which suitable holding bolts 100 may extend for holding the detent members securely in place. Each of the detent members is provided with the stop members 30' and 31, which provide between them a notch 32 having square shoulders. Said notch 32 is adapted to receive the catch portion 21 of the lever 20 or the catch portion 18 of the catch member 17. The stop member 31 is provided with the beveled face 33 for guiding the cooperating catch portion 21 or the 110 cooperating catch portion 18 in the closing movement of the supplemental door 6. It will be noted that the stop members 30' and 31 are mounted upon the standard 34, thereby forming a T-shaped structure. Mounted 115 at the end of the T-shaped structure is the positive stop 35. As will be noted from an inspection of Figure 8, the detent member 29 is provided with a plurality of transversely extending ridges 36-36 providing 120 between them the depressions 37-37. Preferably said ridges have square shoulders. The purpose of the ridges 36-36 and the alternating depressions 37-37 is to permit the insertion of a crow bar or other implement between the detent member 29 and the jamb 9 if sticking should occur. It will be noted that the detent member 29 located on the floor of the car is so positioned that the notch 32 is completely above the floor line. 130

This is clearly indicated in Figures 4, 5 and 6. It will be noted that the notch 32 is open at both of its ends, whereby said notch may be readily cleaned of ice or dirt. Moreover, 5 said notch extends in a line transversely of the car, whereby when the car is being swept out, by means of a broom or similar article, said notch 32 will be cleaned without any particular attention.

10 It will be noted that when the upper catch member 17 is in latching position the trip member 23 must be in its down position, that is to say—said trip member 23 must be in position to permit the catch portion 21 15 of the lever 20 at the bottom of the door jamb to be in latching position. Expressed in other language, it may be stated that if the latching lever 20 at the bottom of the jamb is held upwardly out of latching position, 20 the trip member 23 will hold the upper catch member 17 out of latching position. It will be impossible for the upper catch member 17 to be in latching position at any time when the lever 20 at the bottom of the 25 jamb is out of latching position. Even if the movable jamb got slightly askew, as, for example, when it is not secured to the supplemental door, the portion 31 of the lower detent member 29 will hold the lower 30 latching lever 20 in its uppermost position within a relatively wide range of travel, whereby it will be impossible for the upper catch member 17 to reach latching position before the catch portion 21 has reached the 35 portion 31 of the lower detent member 29. When, as preferred, the jamb is rigidly secured to the supplemental door, there is no substantial skewing effect on the jamb, said jamb always occupying a substantially vertical position. Under these conditions it is 40 manifestly impossible for the upper latching member 17 to be in latching position when the lower latching lever 22 is out of latching position.

45 As illustrated in Figures 5 and 6, the laterally disposed flanges of the channel-shaped post 9 are recessed at their ends as indicated by the numeral 38. The housings 13-13 are similarly recessed. The recesses 38-38 50 are bounded at the ends of the post 9 by the projecting portions 39-39 adapted to ride between the stop members 30' and 31 and the main portion of the detent member 29. The T-shaped construction above referred 55 to, provided by the portion 34 and the stop members 30 and 31, provides a space for receiving the projecting portions 39-39 of the post 9 and the housings 13-13. Referring to the interlocking relationship between the 60 T-shaped construction of the detent members secured to the side sill and side plate of the car (constituting the bottom and top portions, respectively, of said car) and the projecting portions 39-39 of the post 9, said interlocking relationship has the ad-

vantage that if said side sill and side plate should tend to spread, as, for example, in the case of a collision or in the case of overloading, the jamb will act as a tie to resist such spreading.

70 The channel-shaped post 9 provides a space presented inwardly of the car for a timber, known in the art as a nailing strip, by means of which grain doors may be conveniently nailed in place. This nailing strip 75 is indicated by the numeral 40 and is illustrated in Figures 2, 3, and 6. Said nailing strip may extend the length of the post 9 between the housings 13-13 and may be held in position by nails or other securing 80 means extending through the holes 41-41. The grain doors may be nailed to the nailing strip 40 and to the stationary jambs 42-42 (Figure 2). It need not be explained 85 that the ordinary freight car door is not ordinarily sufficiently tight to keep grain and other finely divided lading from escaping. Grain doors are ordinarily provided for this purpose. According to the present invention the securing of the grain doors is very 90 greatly facilitated.

95 Figures 9 and 10 illustrate a modification particularly adaptable for the steel freight cars. According to the embodiment illustrated in said figures, the angles 10-10 have their flanges disposed in positions extending away from one another, that is to say, those flanges which are mounted parallel with the side walls of the car are disposed laterally of the post 9 instead of inwardly 100 of said post. Figure 9 also illustrates a slightly modified form of catch member, said catch member being indicated by the numeral 43. Said catch member 43 is connected to the trip member 23 in a manner 105 to permit a certain amount of swinging movement but preventing longitudinal movement of said trip member 23 relative to said catch member 43. The catch member 43 has pivotal connection with the housing 110 13 and is provided with a catch portion 44, which operates in a manner similar to the action of the catch portion 18 of the catch member 17 shown in Figure 4.

115 Figure 11 illustrates an embodiment suitable for a wooden door jamb. The wooden door jamb is indicated by the numeral 45 and is provided at the top and bottom thereof with the housing 46. Said housing 46 may be secured to the wooden post 45 by any preferred means and is recessed in the way described in connection with Figure 5 whereby to cooperate with the T-shaped construction involving the support 34 and the stop members 20' and 31 of the detent member 120 29 shown in Figure 8.

125 Figures 14, 15, 16 and 17 illustrate structures which are peculiarly adapted for the application of grain doors. According to the structure shown in Figures 14 and 15, 130

the angles 10—10, which have substantially abutting flanges placed adjacent to the car wall, have on their other flanges, that is, the flanges extending toward the interior of the car, a plurality of angles secured thereto to form grooves, indicated by the numerals 47—47 for the reception of grain doors, which grain doors are indicated by the numerals 48—48. According to the construction 10 illustrated in Figure 16, the angles 10—10 are replaced by Z-bars 49—49, which have cooperating therewith certain angles 49'—49' to provide the grooves 47—47 for receiving the grain doors 48. According to the construction shown in Figure 17, special 15 structural shapes are illustrated for providing the grooves 47—47. The advantages of the structure shown in Figures 14 to 17 inclusive are as follows: After grain doors have been nailed in place inside of a box car, they are frequently considerably mutilated when removed. In order to remove 20 said grain doors, an operator will pry same loose so that the nailed edges are often mutilated and are not suitable for renailing. According to the embodiment of the invention 25 illustrated in Figures 14 to 17 inclusive, only one end of each grain door need be nailed in place, the other ends being disposed within the grooves 47—47. In removing the grain doors the operator will have to pry loose only one end of each grain door, so that the life of each grain door is doubled.

35 Figure 18 illustrates a preferred construction of the trip member 23 and its cooperating parts. As illustrated in Figure 18, the trip member is capable not only of a movement in a vertical direction, but has a slight 40 movement toward and away from the jamb 9. In order to permit the latter mentioned movement, the straps 27 are arranged to only loosely enclose said trip member 23. Said trip member 23 is provided with the 45 catch portion 50, which is adapted to catch over one of the straps 27. By reason of this construction, when it is desired to hold the trip member 23 in its uppermost or unlatching position, it is only necessary to 50 move the trip member away from the jamb slightly, so that the catch portion 50 will rest upon one of the straps 27. When the jamb 9 is moved to its home position, the 55 jar attending such movement will cause the catch portion 50 to move from the corresponding strap 27, allowing the trip member 23 to fall, allowing the latches at the upper and lower ends of the jamb to assume their latching positions.

60 Though certain preferred embodiments of the present invention have been illustrated for the purposes of description, it is to be understood that many modifications may be made without departing from the spirit of 65 the invention. It is intended to cover all

such modifications that fall within the scope of the appended claims.

What is claimed is:

1. A car having a side door opening, a movable jamb in said opening, means for automatically locking said jamb at its top and bottom when said jamb is moved to a predetermined position, and means for preventing the locking at the top of said jamb except when said jamb is locked at its bottom.

2. A car having a side door opening, a movable jamb in said opening, said jamb being provided with interchangeable latch supporting members at its upper and lower extremities, detent members mounted on said car at the top and bottom boundaries of said door opening, said detent members and said latch supporting members being provided with overlapping portions whereby to prevent spreading of the top and bottom portions of said car.

3. A car having a door opening, a pair of doors for closing said opening, said doors having adjacent edges adapted to be brought together for closing said door opening, one of said doors including a jamb movable therewith, means for automatically locking said jamb at its top and bottom when said jamb is moved to a predetermined position, and means capable, in a single movement, of unlocking said jamb at its top and bottom.

4. A car having a door opening, two doors having cooperating edge portions for closing said door opening, one of said doors having secured thereto inwardly of said car a jamb movable therewith, and means for automatically locking said door at its top and bottom when said jamb is moved to a predetermined position, said locking means including interchangeable latch supporting members at the upper and lower extremities of said jamb, said locking means also including detent members carried by said car at the upper and lower portions thereof, said detent members and said latch supporting members being provided with overlapping portions for preventing the spreading of said top and bottom portions of said car.

5. A car having a door opening, two doors having cooperating edge portions for closing said door opening, one of said doors having secured thereto inwardly of said car a jamb movable therewith, positive means for automatically locking said door at its top and bottom when said jamb is moved to a predetermined position, and releasing means, operable in a single movement disposed inwardly of said car for releasing 125 said locking means.

6. A car having a door opening, a door jamb movable longitudinally of said opening, means for automatically locking said jamb at its top and bottom, said means in-

- cluding a pair of latching members, and means for preventing the locking at the bottom of said car except when locking is effected at the top of said car.
5. 7. A railway car having a door opening, a jamb movable longitudinally of said car, and a pair of slidable doors cooperating with said jamb, said jamb comprising an angular construction adapted to receive a 10 nailing strip, the reentrant angle of said angular construction being presented transversely and inwardly of said car.
8. In combination, in a railway car having a door opening, a pair of doors slidable 15 to close said opening, said doors having edges adapted to interfit with one another, one of said doors having secured thereto a jamb movable therewith, latch means for locking said jamb both at the top and bottom when said jamb is moved to a predetermined position, and means operable in a single movement for releasing said locking means, said releasing means including portions for preventing the locking of said 20 jamb at its top except when said jamb is locked at its bottom.
9. A railway car having a door opening, a jamb movable longitudinally of said car, and a pair of slidable doors cooperating 25 with said jamb, said jamb comprising a channel-shaped construction adapted to receive a nailing strip, the channel of said construction being presented transversely and inwardly of said car.
- 30 10. A car having a door opening and a door jamb movable longitudinally of said car, said door jamb comprising a pair of vertically placed angle members having flanges disposed parallel with the wall of 35 said car and having other flanges extending toward the interior of said car, said last mentioned flanges being fashioned to facilitate the attachment and holding of a co-operating strip therebetween.
- 40 11. A car having a door opening, a pair of doors to close said opening, a jamb movable longitudinally of said car for cooperating with said doors, said jamb comprising a channel-shaped construction, and interchangeable latch supporting members 45 mounted at the top and bottom of said jamb.
- 50 12. A car having a door opening, a movable jamb in said opening, said jamb comprising a channel-shaped construction and holding members mounted at the top and bottom of said jamb, and latch members carried by said holding members, said holding members being fashioned to readily receive said latch members, said channeled 55 construction being fashioned to cooperate with said holding members to hold said latch members against displacement.
- 60 13. A car having a door opening, a jamb movable longitudinally of said car, said jamb comprising a channeled construction 65 including a pair of angle members placed together, latch members at the top and bottom of said jamb, holding members for said latch members, said holding members having laterally presented studs fitting in holes 70 in said channeled construction whereby said holding members are secured in position.
14. A car having a door opening, a main door for said opening, a supplemental door, a jamb secured to said supplemental door 75 on the inner face thereof, said jamb including a channeled construction having its channeled face presented inwardly of said car.
15. A car having a door opening, a main 80 door for said opening, a supplemental door for said opening, a door jamb secured to said supplemental door on the inner face thereof, said door jamb having secured thereto latch members at its top and bottom portions, and interchangeable housings 85 for said latch members.
16. A car having a door opening, a pair 90 of doors to close said opening, one of said doors having secured thereto on its inwardly presented face a vertically extending movable door jamb, said door jamb having locking elements at its top and bottom portion, detent members cooperating with said locking elements, said detent members being interchangeable at the top and bottom of said 95 jamb, said detent members and said locking members having interfitting slidable portions.
17. A car having a door opening and a 100 door jamb movable longitudinally of said car, said door jamb including a vertically placed angle member, the reentrant angle of said angle member being presented transversely and inwardly of said car, the flanges 105 of said angle member being fashioned to facilitate the attachment and holding of a co-operating strip.
18. A railway car having a door opening, a movable jamb in said opening, latch members 110 at the top and bottom of said jamb for holding same in predetermined position, interchangeable members for pivotally supporting said latch members, and detent members at the top and bottom of said 115 jamb, said detent members having runway portions of T-shaped cross section, said jamb having portions cooperating with said T-shaped portions to maintain said jamb and said detent members in cooperative relationship.
19. A car having a door opening, a pair 120 of doors to close said opening, a jamb movable longitudinally of said car for cooperating with said doors, said jamb including an angle member adapted to receive a nailing strip in its reentrant angle, and interchangeable latch supporting members mounted at the top and bottom of said jamb.
20. A door jamb comprising a channeled 125

construction made up of two angles placed together, said channeled construction having its channeled face presented inwardly of said car, housings within said inwardly presented face, one of said housings being mounted at the top and the other at the bottom of said channeled construction, each of said housings being provided with a slot adapted to receive a locking member, said 10 slots being closed by adjacent flanges of said angles

21. A railway car having a door opening, a pair of doors for closing said opening, a door jamb in said opening movable longitudinally of said car, interchangeable housings mounted at the top and bottom of said jamb, locking elements supported by said housings and interchangeable detent members cooperating with said locking members 20 for locking said jamb in a predetermined position.

22. A railway car having a door opening, a pair of doors for closing said opening, a door jamb in said opening movable longitudinally of said car, interchangeable housings mounted at the top and bottom of said jamb, locking elements supported by said housings and interchangeable detent members cooperating with said locking members 30 for locking said jamb in a predetermined position, said members being formed with guiding portions whereby when said jamb is moved to said predetermined position said members will be moved automatically into locking engagement.

23. A railway car having a door opening, a pair of doors for closing said opening, a door jamb in said opening movable longitudinally of said car, interchangeable supporting members mounted at the top and bottom of said jamb, locking elements supported by said supporting members and detent members cooperating with said locking members for locking said jamb in a predetermined position, said detent members being formed with guiding portions whereby when said jamb is moved to said predetermined position said members will be moved automatically into locking engagement.

24. A car having a door opening, a movable jamb in said opening, said jamb comprising an angle member and holding members mounted at the top and bottom of said jamb, and latch members carried by said holding members, said holding members being fashioned to readily receive said latch members, said angle member being fashioned to cooperate with said holding members to hold said latch members against displacement.

25. A car having a door opening, a main door for said opening, a supplemental door, and a jamb cooperating with said doors and mounted interiorly of said car, said jamb 60 including an angle member having its re-

entrant angle presented inwardly of said car.

26. Means for holding a sliding door detachably in a predetermined position, including a vertically mounted member, a 70 pair of detent members mounted above and below said predetermined position of said vertical member, each of said top and bottom members having a T-shaped projection the head of which is provided with a guiding surface, and each of said top and bottom members having an abutment portion arranged at right angles to said T-shaped projection, and latch members carried by said vertical member adapted to cooperate 80 with said T-shaped projections and with said abutment portions.

27. A railway car having a door opening, a pair of sliding doors for closing said opening, one of said doors being provided with a jamb movable therewith, said jamb being provided with a recess for securing cooperating material to said jamb, said recess being presented transversely and inwardly 90 of said car.

28. A railway car having a door opening, a pair of sliding doors for closing said opening, a door jamb secured to one of said doors, locking means for locking said jamb in a predetermined position both at the top 95 and bottom of said jamb, and unitary unlocking means for releasing said jamb in a single movement.

29. A railway car having a door opening, a pair of sliding doors for closing said 100 opening, a door jamb secured to one of said doors, locking means for locking said jamb in a predetermined position both at the top and bottom of said jamb, and unitary unlocking means for releasing said 105 jamb in a single movement, said jamb being provided with grooved portions for receiving and holding cooperating material.

30. A car having a side door opening, a movable jamb in said opening, a door secured to said jamb and movable therewith, a second door adapted to cooperate with said jamb, and independently movable relative thereto, means for automatically locking said jamb at its top and bottom when 110 said jamb is moved to a predetermined position, and means capable, in a single movement, of unlocking said jamb at its top and bottom.

31. A railway car having a door opening, a pair of doors for closing said opening, a door jamb in said opening movable longitudinally of said car, interchangeable housings mounted at the top and bottom of said jamb, locking elements supported by said 120 housings and detent members cooperating with said locking elements for locking said jamb in a predetermined position.

32. A railway car having a door opening, a pair of doors for closing said opening, a 130

- door jamb in said opening movable longitudinally of said car, interchangeable housings mounted at the top and bottom of said jamb, locking elements supported by said 5 housings and detent members cooperating with said locking members for locking said jamb in a predetermined position, said members being formed with guiding portions whereby when said jamb is moved to said 10 predetermined position said members will be moved automatically into locking engagement.
33. A car having a door opening, a movable door jamb mounted in said opening, said 15 door jamb having latch members mounted at the upper and lower portions thereof, a trip member for simultaneously operating said latch members, said trip member and said door jamb having cooperating portions 20 whereby said trip member may be held in unlatching position.
34. A car having a door opening, a pair of doors for closing said opening, said doors having adjacent edges adapted to be brought 25 together for closing said door opening, one of said doors including a jamb permanently secured thereto and movable therewith, means for automatically locking said jamb at its top and bottom when said jamb is 30 moved to a predetermined position, and means capable, in a single movement, of unlocking said jamb at its top and bottom.
35. A car having a door opening, a pair of doors for closing said opening, said doors 35 having adjacent edges adapted to be brought together for closing said door opening, one of said doors including a jamb movable therewith, and means for automatically locking said jamb at its top and bottom when 40 said jamb is moved to a predetermined position, said jamb being provided with means interfiting with said car whereby to operate as a tie between the top and bottom portions of said car.
45. 36. A car having a door opening, two doors having cooperating edge portions for closing said door opening, one of said doors having secured thereto inwardly of said car a jamb movable therewith, positive means 46 for automatically locking said door at its top and bottom when said jamb is moved to a predetermined position, and releasing means disposed inwardly of said car for re- leasing said locking means, said jamb being provided with means interfiting with said car whereby to operate as a tie between the top and bottom portions of said car.
37. A railway car having a door opening, a pair of doors for closing said opening, a door jamb in said opening movable longitudinally of said car, interchangeable supporting members mounted at the top and bottom of said jamb, locking elements pivotally supported by said supporting members, and detent members cooperating with said locking elements for locking said jamb in a predetermined position.
38. In side door construction, the side sill of a car, door means slideable longitudinally of said car, and means for locking said door in predetermined position, said locking means including a latch upon said door means and a detent mounted upon said sill, said detent member having an open-ended notch for receiving said latch, said notch being disposed in a direction transversely of said car.
39. A railway car having a door opening, a pair of doors for closing said opening, a door jamb in said opening movable longitudinally of said car, interchangeable latch carrying members mounted at the top and bottom of said jamb, latching elements supported by said members, and detent members carried by the upper and lower portions of 85 said car cooperating with said latching members for locking said jamb in a predetermined position.
40. A railway car having a door opening, a pair of doors for closing said opening, a door jamb in said opening movable longitudinally of said car, interchangeable latch carrying members mounted at the top and bottom of said jamb, latching elements supported by said members, and detent members carried by the upper and lower portions of 90 said car cooperating with said latching members for locking said jamb in a predetermined position, said detent members having cooperating overlapping portions to prevent 95 the spreading of the top and bottom portions of the car.

Signed at Chicago, Illinois, this 6th day of August, 1924.

KENNETH J. TOBIN.
WILLIAM W. DARROW.

CERTIFICATE OF CORRECTION.

Patent No. 1,533,620.

Granted April 14, 1925, to

KENNETH J. TOBIN ET AL.

It is hereby certified that error appears in the printed specification of the above numbered patent requiring correction as follows: Page 6, lines 43, 44 and 108, claims 10 and 17 respectively, and page 7, lines 87 and 88, claim 27, for "cooperating" read "coopering"; and the said Letters Patent should be read with these corrections therein that the same may conform to the record of the case in the Patent Office.

Signed and sealed this 23rd day of October, A. D. 1928.

(Seal)

M. J. Moore,
Acting Commissioner of Patents.
